S. KUCHARSKI

FILM FEED MECHANISM FOR PHOTOGRAPHIC CAMERAS

Filed March 19, 1923

Inventor:
Stanislaus Kucharski
by J. Wetter
Attorney.

UNITED STATES PATENT OFFICE.

STANISLAUS KUCHARSKI, OF CHARLOTTENBURG, GERMANY, ASSIGNOR TO ALFRED HUBER AND WOLFGANG SIMONS, OF BERNE, SWITZERLAND.

FILM-FEED MECHANISM FOR PHOTOGRAPHIC CAMERAS.

Application filed March 19, 1923. Serial No. 626,207.

To all whom it may concern:

Be it known that I, STANISLAUS KUCHARSKI, a citizen of the German Republic, residing at Charlottenburg, Germany, have 5 invented new and useful Improvements in Film-Feed Mechanism for Photographic Cameras, of which the following is a specification.

In photographic apparatus for producing 10 a considerable number of individual views on roll-films it is advantageous to produce the film-feed by simple motions of a drawbar regulated so as to obtain uniform lengths of pictures. The present improvements 15 attain this object in a very simple manner by causing the drawbar to advance the film-feed drum by means of a flexible band, for one image after another and by providing a film-feed regulating device 20 for automatically adjustable film transporting device adapted to produce uniform lengths of pictures in spite of increasing diameter of the drum and with very simple means.

25 The drawing shows an example of construction embodying the invention.

In the interior of a camera-body *a* are located two drums carrying a film adapted to be fed forward by the up and down motion of a drawbar *b*. On the drum *c* is wound the unexposed negative film. The dotted line *d* indicates the course of the film towards the lower drum. The latter is mounted on a transporting disc *g* by means 30 of a pair of driving studs or pins *e* and *f*. This transporting disc is surrounded by a toothed ring *h* adapted to turn the transporting disc in one direction by means of a ratchet pawl *i*. On the outside of the 35 toothed disc *h* there is a flexible band *k* attached to it at *l*. One end of the band is fixed on the axle of the drum *c* by means of spiral shaped elastic windings or spring coils *x*, and the other end of the band is fixed to the drawbar *b*. The latter carries a 40 spring pawl *v* which at every downmotion of the said bar turns a tooth wheel or counting disc *m* carrying a counting disc forward one tooth, the accidental return motion of the counting disc *m* being prevented by a pawl *n*, while a pawl *o* is provided to prevent the transporting drum from sliding back.

On the toothed disc *m* is fixed a cam *p* 45 calculated in such a manner that it serves

to limit the stroke of the drawbar *b* by the impact of the pin *s* with the hook-shaped end *t* of the lever *r*, the time of which impact depends on the position of the levers *q* and *r*. 60

The position of the lever *q*, which has a pad *u* kept in contact with the circumference of the cam *p* is adjusted by the turning of the cam. Every turning of the cam by the downmotion of the drawbar *b* adjusts 65 the position of the lever *r* for the subsequent upmotion of the drawbar, and consequently the length of the stroke of the latter.

A spring *y* attached to the lever *r* and the bar *b* is provided for balancing the weight of the levers *q* and *r* and pressing the pad *u* against the cam *p*. 70

What I claim is:

1. In a roll-film photographic apparatus, 75 a film holding and transporting mechanism comprising in its construction a pair of parallel drums, viz. a delivery drum and a receiving drum, an axle on which said delivery drum is mounted, a spiral spring 80 coiled on said axle, a transporting disc adapted to turn the receiving drum, a drawbar movable longitudinally by hand, a flexible transporting band attached at one end to the said drawbar and at the other 85 end to said spiral spring, the said transporting band being guided over the circumference of the transporting disc and adapted to impart motion to the said disc, an adjustable abutment adapted to limit the stroke of 90 the said drawbar, and a regulating device adapted to adjust the position of the said abutment at every stroke of the drawbar, in one direction and to shorten the subsequent stroke of the same, in the opposite direction substantially as described. 95

2. In a roll film photographic camera, a film holding and transporting mechanism comprising a pair of parallel film holding and transporting drums, viz. a delivery drum 100 and a receiving drum, an axle on which said delivery drum is mounted, a spiral spring coiled on said axle, a longitudinally movable draw bar adapted to be operated by hand, a flexible transporting band attached at one 105 end to the draw bar and at the other end to said spiral spring, a transporting disc connected with the receiving drum over the circumference of which disc the said transporting band is guided, a cam and cam shaft 110

adapted to be turned forward at every inward stroke of the draw bar, an abutment adapted to limit the stroke of the draw bar, and mechanism adapted to be adjusted 5 at every motion of the cam so as to displace said abutment.

3. In a roll-film photographic camera, a film holding and transporting mechanism comprising a delivery drum, an axle on 10 which said delivery drum is mounted, a spiral spring coiled on said axle, a transporting disc parallel to the said delivery drum, a film drum detachably mounted on the said transporting disc, a draw bar, a flexible 15 driving band attached at one end to said drawbar and at the other end to said spiral spring, the said transporting band being guided over the circumference of the said transporting disc and adapted to turn it

while travelling towards the receiving drum, 20 a cam-shaft carrying a regulating cam and ratchet-wheel located between the two drums, a ratchet pawl attached to the drawbar and adapted to turn the ratchet wheel forward one division at every return stroke 25 of the drawbar, thereby adjusting the position of the cam so that it limits the subsequent forward stroke and an abutment device adapted to limit the stroke of the drawbar according to the position of the 30 regulating cam, substantially as described.

In testimony whereof I have hereunto set my hand.

STANISLAUS KUCHARSKI.

Witnesses:

HENRY HUBER,
CARL MERBEIN.
